UNITED STATES PATENT OFFICE.

THEODOR OTTO, OF SCHKENDITZ, ASSIGNOR TO THE FIRM OF J. POHLIG, OF COLOGNE, GERMANY.

TRUCK FOR VEHICLES FOR ROPEWAYS.

SPECIFICATION forming part of Letters Patent No. 444,109, dated January 6, 1891.

Application filed September 20, 1890. Serial No. 365,645. (No model.) Patented in France December 28, 1885, No. 173,193; in Belgium December 28, 1885, No. 71,390; in Austria-Hungary May 13, 1887, No. 3,556 and No. 22,064; in England May 23, 1887, No. 7,507; in Italy June 30, 1888, XXII, 23,320, XLVII, 322, and in Spain June 30, 1888, No. 8,085.

To all whom it may concern:

Be it known that I, THEODOR OTTO, civil engineer, a subject of the King of Prussia, residing at Schkenditz, Prussia, German Empire, have invented certain new and useful Improvements in Trucks for Vehicles for Ropeways, (for which I have obtained Letters Patent in the following countries: Austria-Hungary, No. 3,556 and No. 22,064, dated May 13, 1887; France, No. 173,193, dated December 28, 1885; Belgium, No. 71,390, dated December 28, 1885; Italy, Vol. 22, No. 23,320, Vol. 47, No. 322, dated June 30, 1888; Great Britain, No. 7,507, dated May 23, 1887, and Spain, 15 libro 6, folio 385, No. 8,085, dated June 30, 1888;) and I do hereby declare the following to be a full, clear, and exact description of the invention, such as will enable others skilled in the art to which it appertains to 20 make and use the same, reference being had to the accompanying drawings, and to letters of reference marked thereon, which form a part of this specification.

My invention relates to trucks for vehicles 25 for ropeways. The trucks heretofore employed for vehicles of ropeways consist of two rollers which move upon the carrying or standing rope and are held in a frame from which the transporting - vessel is suspended by means 30 of a hanger pivoted to the said frame. In most cases the latter consists of a cast-iron piece, which has on one side two projecting bolts, upon which the rollers are turning round. Frames of this kind do not form a 35 rigid whole. Their parts are therefore liable to become loose, and especially the bolts will bend in time while the nave-holes of the rollers are getting conical. This causes them to assume an oblique position, in which the 40 trucks are liable to slip off the rope. For obviating these defects according to the present invention the rollers turn on axles which are bedded at both ends in the frame. The latter consists of two steel plates with a cast-iron piece between them, to which they are 45 riveted. The axles are made hollow and serve as receptacles for lubricating material.

In the accompanying drawings, Figures 1 and 2 illustrate part of a ropeway having a

truck constructed according to the present 50 invention. Figs. 3, 4, and 5 show a front-elevation, horizontal section, and side elevation of the improved truck. Fig. 6 shows the intermediate piece in vertical section, and Fig. 7 a bolt constituting an axle for the rollers in 55 elevation.

In Figs. 1 and 2, A designates the carrying or standing rope whereon the truck B moves, to which the hanger D for suspending the 60 transporting-vessel F is pivoted.

The truck comprises the two rollers a, moving upon the rope A and adapted to turn between the two plates b upon bolts d. The two plates b are held in the middle by an intermediate piece g, with which they are firmly 65 connected by rivets or screws h in such a manner that they remain at a distance which corresponds to the length of the naves of the rollers. This distance between the plates b is further insured by the two bolts d, which 70 are provided at both ends at d' and d'', Fig. 7, with screw-threads. As shown in this figure, the diameter of the part d, serving as an axle for the rollers, is greater than that of the screw-threaded part d', but smaller than the 75 diameter of the screw-threaded part d'', so that the bolts d can be removed without taking off one of the plates b. The bolts d are made hollow, and after the removal of the screw d' they can be filled with a lubricant, 80 which is allowed to pass through holes i in the periphery of the bolts to the wearing-surfaces of the said bolts and of the hole in the naves of the rollers. The intermediate piece 85 g and the plates b are provided with a hole o for the reception of the pivot f, extending from the hanger D and held in its place by the washer m and screw p. Through the lubricating-hole r lubricant can be conducted 90 to the pivot f.

By reason of the described arrangement of the truck the rollers a cannot assume an oblique position relatively to the hanger D, thus obviating the liability of the rollers to 95 slip off the rope.

Having now described my invention, what I claim is—

1. A truck for vehicles of ropeways, which

comprises the plates *b*, taking between them the two guide-rollers *a*, the intermediate piece *g*, provided with the hole *o* for the pivot *f* of the hanger *D*, and the bolts *d*, screwed into 5 the plates *b* and serving to support the said rollers *a*, substantially as described.

2. A truck for vehicles of ropeways, which comprises the rollers *a*, the plates *b*, the intermediate piece *g*, and the bolts *d*, that have 10 a cavity for the reception of a lubricant and

possess at one end a filling-hole adapted to be closed by means of a screw *d³* or the like, substantially as described.

In testimony whereof I affix my signature in presence of two witnesses.

THEODOR OTTO.
